INVENTOR
Charles D. Earll.

UNITED STATES PATENT OFFICE.

CHARLES I. EARLL, OF NEW YORK, N. Y.

TROLLEY-CATCHER.

1,249,729.

Specification of Letters Patent. Patented Dec. 11, 1917.

Application filed April 20, 1916. Serial No. 92,861.

To all whom it may concern:

Be it known that I, CHARLES I. EARLL, a citizen of the United States of America, and resident of city, county, and State of 5 New York, have invented certain new and useful Improvements in Trolley-Catchers, of which the following is a specification.

My invention relates to trolley catchers and similar devices for the control of the 10 trolley ropes of electric cars.

The object of my invention is to provide a trolley catcher which shall be simple and effective in its construction and operation, one that is especially adapted to operate 15 effectively where low trolley pole pressures are employed and one which is particularly convenient as regards its manipulation and care.

My invention consists in a novel construction and arrangement of parts hereinafter pointed out and described.

In the drawings accompanying and forming part of this specification Figure 1 is a transverse section of a trolley catcher embodying the preferred form of my invention. Fig. 2 is a section on line 2—2 of Fig. 1. Fig. 3 is a partial section on line 3—3 of Fig. 2. Fig. 4 is a partial section on line 4—4 of Fig. 1. Fig. 5 is a partial section corresponding to Fig. 1 showing certain parts in different operative positions. Fig. 6 is a top view of the check pawl 14. Fig. 7 is an end view of the tension spring hub 6, and Fig. 8 is a partial section of 35 the shell 2.

The trolley catcher is adapted to be received into a socket secured to the dash or end of the car in a manner which is well understood and not illustrated herein.

40 The case is comprised of two parts, the back 1 and the front or shell 2. The back is preferably made of a casting and has the teeth 3 formed therein. The front or shell 2 is preferably made of drawn steel and is provided with an opening 4 through which the trolley rope passes. Mounted centrally in the case is the shaft 5 to the front end of which is secured the tension spring hub 6 and on the rear end in threaded engagement is the nut 7 held from turning by a cotter pin 8. The tension spring hub extends inwardly and receives the inner end of the tension spring 9. The outer end of the tension spring is engaged with the drum 10. The tension spring hub has a flange 11 which, on the side adjacent to the shell

2, is provided with ratchet teeth or projections 12 adapted to engage corresponding teeth or projections 35 stamped or formed in the shell 2 so that the tension spring hub 60 may be turned in the direction which will wind up the tension spring, but is prevented by said projections from turning in the opposite direction. The elasticity of the shell is sufficient to permit this turning of the 65 tension spring hub. On the rear end of the drum is formed the stud 13 on which is mounted the check pawl 14 and the counter balance 15. The check pawl is adapted to engage the teeth 3 of the back when in its 70 outer position but clears said teeth when it rests against the banking 16 in its inner position.

Pivoted to the check pawl is the centrifugal pawl 17 which in its inner position 75 rests against the banking 18 and in its outer position is adapted to engage the teeth 3 of the back. It is normally held in its inner position by the spring 19. The centrifugal pawl has an extension 20 which engages a 80 slot 21 in the counter balance, the counter balance being pivotally mounted on the stud 13 on which the check pawl is mounted. This counter balance is of such size and form as to counter balance the effect of gravity upon 85 the centrifugal pawl as the drum revolves back and forth, so that when the trolley jumps the wire and starts upwardly in a rapid motion, in a manner which is well understood, the centrifugal pawl will fly outward 90 when it has obtained the same speed or acceleration, no matter at what point in the revolution it happens to be when the trolley jumps. The arrangement of the check pawl pivoted to the drum and the centrifugal 95 pawl pivoted to the check pawl is similar to that shown in my Patent No. 1,110,758 of Sept. 15th, 1914, and this feature of my present invention retains all of the advantages described in my former patent in addition to the advantages resulting from having a practically perfectly balanced centrifugal pawl. The check pawl 14 consists, or is formed of, two parallel webs 22 joined together at the end 23 and the centrifugal 100 pawl and counter balance are received between these two webs, the centrifugal pawl being pivoted on the pin 34 and the counter balance on the stud 13 on the drum. The web of the check pawl nearest the drum is 110 provided with a flange or extension 24 which passes under the lug 25 in such a manner

that the check pawl is retained in position on the stud 13 when the trolley catcher is assembled. When, however, the drum is taken from the case and the centrifugal pawl spring 19 is unhooked, the check pawl may be readily turned outwardly until the flange 24 is out of range of the overhanging lug 25 and freely lifted from the stud 13. By means of this construction the assembling 5 and disassembling is greatly facilitated. The side of the drum is provided with an opening 26 which is of sufficient size to receive the knotted end of the trolley rope. This opening is provided with a narrower extension 27 against which the rope is pulled after the knot has been passed through the opening 26 to attach the rope to the drum. 28 is a stud formed on the face of the drum on which is mounted the drum check pawl 29. 20 The spring 30, engaging the stud 28 and the pawl 29, tends to move the pawl outwardly. The end 31 of the pawl extends out in the plane of the teeth 3 of the back and the pawl is provided with an arm 32 which extends 25 through an opening 33 in the flange of the drum out over the face of the drum so that when the rope is wound on the drum it will pass over and hold down the arm 32 against the face of the drum, and when the rope is 30 unwound from the drum to that extent which frees the arm 32, the spring 30 will push the pawl outwardly in the path of the teeth 3 in the back and prevent the drum from turning in the direction which winds 35 up the trolley rope thereon which is the direction in which the tension spring 9 tends to turn the drum. It will thus be seen that the drum will be automatically locked from running away under the action of the tension 40 spring before the rope is detached from the drum. After the rope has been attached to the drum by passing a knot through the opening 26, the arm 32 of the pawl 29 is pressed downwardly thus releasing the drum 45 and permitting the tension spring to turn it in the direction to wind up the rope. It is held down manually until the drum has turned sufficiently to bring the arm under the rope after which the rope holds the arm 50 down until it is again unwound.

Having thus described my invention, what I claim is:

1. In a trolley catcher the combination with a drum and a trolley rope secured thereto, of means for automatically locking the drum at a predetermined point in the unwinding of rope therefrom.

2. In a trolley catcher the combination with a drum, a trolley rope secured thereto, and a spring adapted to rotate said drum to wind up said rope, of means for automatically locking said drum against the action of said spring at a predetermined point in the unwinding of rope from said drum.

65 3. In a trolley catcher the combination

with a drum, a trolley rope secured thereto and a spring adapted to rotate said drum to wind up said rope, of means independent of the means by which said rope is secured to said drum for automatically locking said drum against the action of said spring. 70

4. In a trolley catcher the combination with a drum, a trolley rope secured thereto and a spring adapted to rotate said drum to wind up said rope, of means independent of the means by which said rope is secured to said drum for automatically locking said drum against the action of said spring at a predetermined point in the unwinding of the rope. 75

5. In a trolley catcher the combination with a case, of a spring actuated drum mounted in said case, a trolley rope secured to said drum, means to automatically check the drum when the speed at which the rope is unwound therefrom exceeds a predetermined limit, and means locking the drum to the case at a predetermined point in the unwinding of rope therefrom. 80

6. In a trolley catcher the combination with a case, of a spring actuated drum mounted in said case, a trolley rope secured to said drum, means to automatically check the drum when the speed at which the rope is unwound therefrom exceeds a predetermined limit, and means locking the drum to the case at a predetermined point in the unwinding of rope therefrom, said means being independent of the means by which the rope is secured to the drum. 85

7. In a trolley catcher the combination with a case having a tooth or abutment, a spring actuated drum mounted in said case, a centrifugally controlled checking device connected with said drum and adapted to engage said tooth when the drum is turned rapidly in one direction, and means connected with said drum and adapted to engage said tooth or abutment to prevent the drum from turning in the opposite direction. 90

8. In a trolley catcher the combination with a drum adapted to receive the trolley rope, of a lock pawl pivoted to said drum, a centrifugal pawl pivoted to said lock pawl, and a counter balance connected with said drum and said centrifugal pawl adapted to substantially counterbalance the effect of gravity upon said centrifugal pawl. 95

9. In a trolley catcher the combination with a case, of a drum mounted in said case, a pawl pivotally mounted on said drum and adapted to engage said case, a centrifugal pawl pivotally mounted on said pawl adapted to engage said case and a counterbalance mounted on said drum and connected with said centrifugal pawl. 100

10. In a trolley catcher the combination with a case, of a drum mounted in said case, a pawl pivotally mounted on said drum and adapted to engage said case, a centrifugal 105

pawl pivotally mounted on said pawl adapted to engage said case and a counterbalance mounted pivotally concentric with said pawl on said drum and connected with said centrifugal pawl.

11. In a trolley catcher the combination with a case, one side of which is adapted to yield elastically, of a shaft mounted in said case having flanges secured thereto adapted 10 to engage the exterior of said case, one of

said flanges having engaging projections adapted to engage projections on said case.

In testimony whereof, I have signed my name to this specification in the presence of two subscribing witnesses.

CHARLES I. EARLL.
